United States Patent

Des. 242,352
Patented Nov. 16, 1976

242,352

SINK SPRAYER

Tim M. Uyeda, South San Gabriel, Calif., assignor to
Chicago Specialty Manufacturing Co., Skokie, Ill.

Filed Feb. 19, 1976, Ser. No. 659,204

Term of patent 14 years

Int. Cl. D23—01

U.S. Cl. D23—35

FIG. 1.

FIG. 2.

FIG. 3.

FIG. 4.

FIG. 5.

FIG. 6.

FIG. 1 is a perspective view of a sink sprayer, showing my design.

FIG. 2 is a side elevational view, the opposite side being a mirror image of the side shown.

FIG. 3 is a front elevational view.

FIG. 4 is a rear elevational view.

FIG. 5 is a top plan view.

FIG. 6 is a bottom plan view.

I claim:

The ornamental design for a sink sprayer, as shown and described.
